M. BUCHHOLZ

PROTECTION OF LIQUID INSULATED ELECTRIC APPARATUS

Filed April 16, 1925

Inventor:
Max Buchholz

by Atty.

UNITED STATES PATENT OFFICE.

MAX BUCHHOLZ, OF CASSEL, GERMANY.

PROTECTION OF LIQUID-INSULATED ELECTRIC APPARATUS.

Application filed April 16, 1925, Serial No. 23,676, and in Germany January 19, 1922.

My invention has reference to a method and means for protecting electric apparatus operating in an insulating liquid, such as oil transformers, oil switches, grounding 5 throttling coils, resistances and the like, and it is one of the important objects of my invention to provide a device of very simple construction and great reliability, and adapted to operate before extensive injuries 10 to the apparatus to be protected can occur by sparking, overloading or other disturbances.

My invention is particularly based on the fact that in the case of disturbances in the operation of the apparatus to be protected 15 or in the case of sparking or other irregularities of operation, or whenever such irregularities are imminent, a rise of temperature will occur which can be utilized for operating suitable protective means associated with 20 the apparatus.

I may for instance utilize a supply of gas such as air, enclosed in a container of metal, glass or other suitable material mounted in the oil filled vessel in close vicinity to the 25 apparatus to be protected, such gas being liberated and allowed to ascend in the insulating liquid whenever a predetermined temperature of the oil is exceeded, owing to an unnormal operation of the apparatus. 30 The ascending air bubbles will then cause a variation of the insulating capacity of the liquid between the terminals of a protective circuit, thereby effecting the switching out of the apparatus or some other protective 35 operation.

The temperature at which the gas is set free should be so selected as to cause the safety device to be operated before the occurring of sparking or of other disturbances. 40 The gas container may be provided with one or a plurality of openings which are closed by readily fusible metals, resins or the like. The gas container may be replaced by a hollow wire or wires which may form part of 45 the electric outfit of the apparatus to be protected. Upon the melting of the closure of the openings in the container, part of the air or other gas enclosed therein under normal or increased pressure, being expanded 50 by the heat of its surroundings, will escape and ascend. Instead of air or a gas, a solid substance or a liquid of low boiling point may be stored in the container and the gases or vapors set free from these substances at 55 an elevated temperature will then act on the

protective circuit. I may even use a plurality of such containers disposed at different points within the vessel, whereby I am enabled to watch the temperature of the insulating liquid at these points. I may even 60 dispense with a container and replace it by some substance capable of remaining unchanged, while being submerged in the insulating liquid under normal conditions, but becoming volatilized or emitting gases or 65 vapors at an elevated temperature, such substances being easier freely arranged in the oil or heated in the insulation of the wires.

A protective device embodying this invention is illustrated in the drawings annexed 70 to this specification by way of example in a purely diagrammatic manner in elevation.

In the drawings, *a* is a transformer casing, *b* is the transformer, *c* are the windings, *d* are the leading-in insulations for the conductors, *e* is an oil switch with a releasing coil *f* comprised in the protective circuit, two terminals of which *F* are arranged in the casing *a* to form a spark gap above the gas container *G* mounted between the windings *c* of the transformer and closed by a fusible plug *H*. The container *G* is filled with air which, on the fusing of the plug *H*, being expelled by the heat generated by an abnormal working of the apparatus, will rise in bubbles ridging the spark gap *F*, whereby the protective circuit is set 80 operating so as to open the oil switch *e* and cut out the transformer.

Besides the form of construction herein 90 shown and described, the invention is susceptible of a variety of other modifications and forms of application of the principle of my invention all of which operate substantially in a similar manner. The means of connecting the contacting device with the releasing circuit and the switching means are 95 open to changes and alterations without any material importance for the operation of the apparatus according to my invention which in its broad aspects comprises the operation of safety devices for electric apparatus or the like, adapted for operation by vapors, fumes, gases or similar emanations liberated and expelled from the insulating medium, and means adapted to be operatively influenced by such emanations, and connected to fuses or equivalent safety means, the instrumentalities shown and described in this specification as embodiments of these principles 100 105 110

being susceptible of modifications without deviating from the spirit of my invention as set forth in the claim.

In the claim the term "gases" is meant to 5 comprise also vapors and fumes.

I claim:

A protective device for transformers or the like comprising a casing in which the transformer is disposed, a supply of insulating liquid surrounding the transformer, a 10 gas chamber arranged in the insulating liquid

between the transformer coils and having an opening closed by a displaceable closure means, a spark gap arranged above said closure means and adjacent thereto, said closure means being displaceable under abnormal working conditions of the apparatus to release the gaseous content of the chamber, the gases on release being adapted to displace the liquid from the spark gap. 15

In testimony whereof I affix my signature. 20
MAX BUCHHOLZ.
